UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed April 26, 1921. Serial No. 464,612.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to tally-strip mechanism, and is in the nature of an improvement upon the patent to F. A. Hart, No. 1,281,160, dated October 8, 1918.

Instead of feeding the tally-strip and carbon-strip from the same roll as in said patent, separate rolls are provided, the two strips being wound on a common receiving roll after passing around the platen.

In the embodiment of the invention illustrated herein, the tally-strip delivery roll is provided at each end with a disk having a beveled friction edge, which is yieldably engaged by a suitable friction brake-member, provision being made of a manually-operable member for withdrawing both of said friction members simultaneously to ineffective position, so as to enable the tally-strip to be drawn forward by the hands without subjecting it to great strain.

Provision may be made of a knurled head connected with the receiving roll, so that the roll may be easily manipulated to wind or unwind strips.

The carbon-strip delivery roll may be supported in the tally-strip device by providing at one end a revoluble member or head having a split tubular portion of suitable resiliency to insert in the hollow end of a core on which the carbon-sheet is wound, and a pin passing through a slot in a plate at one side of the tally-strip mechanism, said slot having an open end to facilitate removal of the pin and the carbon-strip roll from the machine. On the outer side of the slotted plate or member, provision may be made of a spring device supported on the pin and pressing against the outer side of the slotted plate, so as to exert a braking action on the carbon-strip delivery roll.

The supporting member at the other end of the carbon-strip tube may have teeth to enter notches in the core of the carbon-strip roll to prevent relative turning therebetween, and a handle may be connected to this member for use in rewinding said carbon-strip. The pin at this side of the tally-

strip device may be retained in an open slot in the adjacent supporting member by a suitable latching member.

In practice, the carbon-strip and the tally-strip are passed around the platen and secured to the common receiving roll and a work-sheet is passed around the platen outside of the carbon-strip. When typing of one line has been completed, line-spacing of the platen is effected in the usual manner, and by suitable means the action of the line-space mechanism is transmitted to the common receiving roll to draw the carbon-strip and tally-strip forward to a new position for typing. When the typing is completed, the last writing on the tally-strip is at a considerable distance from the receiving roll, and the tally-strip must be advanced to bring the last written line thereon to a position adjacent the common receiving roll, in order to allow the tally-strip to be severed by drawing the same against a fixed knife, which is mounted in the usual position just below the receiving roll.

This advance of the last writing line on the tally-strip may be effected by operating the line-space mechanism until the last line of writing has advanced the desired distance, or, since the method just described involves the taking of considerable time, the tally-strip may be grasped by the hands and pulled upward. The second method is very expeditious, but puts considerable strain on the tally-strip when the friction brake devices are positioned to resist the same. In order to obviate such strain during the drawing forward of the tally-strip, the friction members are withdrawn to ineffective position by manually operated means.

Before severing the used portion of the tally-strip, the portions of the tally-strip and carbon-strip carried by the receiving roll must be removed therefrom. The carbon-strip is then rewound until its leading edge is drawn back of the knife. This enables a portion of the carbon-strip to be used repeatedly until it becomes unfit for use. When this condition is reached, the used portion of the carbon-strip is severed and a new portion brought into use.

Other features and advantages will hereinafter appear.

In the accompanying drawings, Figure 1 is a side elevation, partly in section, showing my invention applied to the

platen-frame of an Underwood standard typewriter.

Figure 2 is a front view, partly in section, of a portion of the tally-strip device, showing the tally-strip roll and the brake device therefor, and also the carbon-strip roll, a section being taken along the axis of the latter and parts broken away sufficiently to show the means whereby the ends thereof are supported.

Figure 3 is a detailed view, showing a knurled head attached to the shaft of the common receiving roll.

Figure 4 is a plan view, showing the brake devices for the tally-strip roll and the means for releasing them simultaneously.

A platen 10 is mounted on an axle or shaft 11, journaled in the ends 12 of a platen-frame 13. The platen-frame 13 also comprises a rear paper-table 14 to guide work-sheets between the platen 10 and the usual feed-rolls 15, whereby the work-sheets may be advanced to the printing line at the front of the platen, to enable typing to be effected thereon by a type 16 carried by a movable type-bar 17 striking through a ribbon 18.

Provision may also be made of a tally-strip mechanism, which may be supported by brackets 19 fixed on the ends 12 of the platen-frame 13. Extending between said brackets 19 are a shaft 20 and a rod 21, which serve to support plates or brackets 22 and 23 at the left and right of the tally-strip mechanism. The structure so far described is in general similar to that disclosed in said patent, No. 1,281,160.

The tally-strip A is placed in the machine in the form of a roll 24 wound on a core or tube 25, which may also be referred to as a roll. The core 25 is loosely mounted on the rod 21 and too rapid unwinding of the tally-strip is prevented by means of disks 26 with beveled friction edges, secured to the core 25, and brake arms 29 having suitably shaped ends 30 in engagement with the beveled edges of disks 26. The arms 29 are pivoted on a rod 31 secured by any suitable means, such as screws 32, to the plates 22 and 23, and are yieldably pressed towards the disks 26 by means of springs 33 having their free ends engaging the arms 29, and their other ends secured to collars 34 on rod 31, the collars being adjustably held in position on said rod 31 by suitable means, such as set-screws 35.

Provision is also made of a carbon-strip B wound upon a hollow core or roll 36, which is supported at its left-hand end by a member 37 comprising a split-expanding tube or head 38, projecting into the end of the core or roll 36 and secured by suitable devices 39 to the enlarged head of a pin 40 extending through an open slot 41 in the plate 22. A beveled disk 42 may be in-

serted between the enlarged head of pin 40 and the plate 22 to properly position the pin, and also to serve as a spool-head for the core 36, on which the carbon-strip is wound. At its outer end, the pin 40 is provided with a reduced threaded portion 43, on which is mounted a nut 44 having a tubular portion adapted to enter the open end of a sleeve or hollow cylinder 45, and to compress a spring 46 between the nut 44 and a shoulder 47 formed in said sleeve 45.

This spring pressure will urge the sleeve 45 and the disk 42 toward each other, so as to press the same against the opposite faces of plate 22 to resist the turning of the core member 37, and, consequently, of the core 36. The pressure of the parts on plate 22 will tend to prevent withdrawal of the pin 40 from the open end of the slot 41, and such pressure may be adjusted by turning the nut 44 on the portion 43.

At its other end, the core 36 is carried by a member 48 provided with a split-expanding tube or head 49 similar to head 38 and inserted in the end of the core 36. The member 48 is also provided with a pin 40 extending through a slot 41 in the plate 23 and having fixed thereon a disk 50 similar to disk 42. On the outer side of plate 23, the pin 40 is provided with a collar 51 to be engaged by a latch 52 pivoted at 53 on the plate 23, and having a projection extending inwardly from its lowest end which may engage in either one of two depressions 54, so as to hold the latch either in the full-line position, shown in Figure 1, with a concave portion thereof fitting over the collar 51, or in the dot-and-dash line position in which the collar 51 is released to enable the pin to be withdrawn from the open slot 41 in the plate 23.

In case the core 36 is to be removed from the machine, the latch 52 will be moved to ineffective position, and the sleeve 45, shown at the left in Figure 2, drawn outwardly to relieve the pressure on the outer surface of plate 22. The core 36 and the supporting members 37 and 48 may then be withdrawn from the tally-strip mechanism, the split-expanding tubes or heads 38 and 49 withdrawn from the old core 36 and inserted in the open ends of another core having a carbon-strip wound thereon, and the assembled parts placed in the machine by moving the pins 40 into the slots 41, the sleeve 45 being pressed outwardly at this time. Upon moving the pins to the bottoms of the slots 41, the latch 52 may be shifted to the full-line position, shown in Figure 1, to secure the right-hand pin and member 48 in position.

Relative rotation between the core 36 and the member 48 may be prevented by providing the latter with projections 55 engaging in slots 56 in the adjacent end of the

core. In order to turn the core 36 by means of the member 48, a handle 57 may be secured to the right-hand pin 40 by suitable means, such as a screw 58.

5 The tally-strip A and carbon-strip B may be passed around the platen and outside of a rod 58^a to a receiving roll 59 having a slot 60 in which the ends of the two strips are inserted, the rod 58^a serving to deflect the 10 strips A and B sufficiently to prevent engagement with the shaft 20. A work-sheet C is then inserted, but guided by the rear paper-table 14, between the feed-rolls 15 and the platen 10, and moved upwardly to 15 position it properly with respect to the printing point. Typing may then be effected on the work-sheet C and the corresponding carbon copy produced on the tally-strip A.

20 When a line of typing has been completed, a line-space lever (not shown) may be actuated to move a slide 61, which, by means of a pawl 62 thereon, will turn a ratchet-wheel 63 and line-space the platen 25 10. The actuating movement of the slide 61 will actuate a link 64 pivoted at 65 to an arm 66, and thereby actuate the latter to cause a pawl 67 to actuate a ratchet 68 on the shaft 20, the pawl 67 being yieldably 30 held in engagement with the ratchet 68 by means of a spring 69. This line-space actuation of shaft 20 will be transmitted by gears 70 thereon to a gear 71 secured to the roll 59, and cause the latter to draw the 35 tally-strip and carbon-strip forward one line-space. The line-space mechanism is, in general, the same as that disclosed in said Patent No. 1,281,160.

When the work is completed, the last line 40 typed on the tally-strip is at a considerable distance from the usual severing knife 72, which is located close to the receiving roll. The tally-strip A and the carbon-strip B are then unrolled from the receiving roll 59, 45 preferably by means of a knurled head 73 secured to the roll, and the carbon-strip B rewound by means of the handle 57 until the leading edge thereof is drawn past the knife. A finger-piece 74 is then depressed 50 to swing about rod 31, a bail comprising two arms 75, connected by a bar 76, and pins 77 extending under the brake-arms 29. This will release the tally-strip roll to enable the 55 tally-strip to be drawn upward by the hands of the operator until the last line typed thereon is above the knife 72. The tally-strip may then be severed, and a fresh portion thereof advanced with the leading end of the carbon-strip to the receiving roll 59 60 and connected therewith by inserting the leading ends of the two strips in the slot 60. The finger-piece 74 may then be restored to its normal position, and a new piece of work started. The leading portion of the carbon-strip can, therefore, be used over and over 65

until it becomes too much worn, and may then be severed from the rest of the strip, and a fresh portion brought into use.

Variations may be resorted to within the scope of the invention, and portions of the 70 improvements may be used without others.

Having thus described my invention, I claim:

1. In a tally-strip device, in combination, a tally-strip roll from which the tally-strip 75 is fed to the platen, disks, one for each end of the tally-strip roll, having beveled edges, a brake device comprising pivoted arms having suitable frictional members to co-operate with the beveled edges of said disks, a pivoted bail having arms extending under the brake arms, and a manually-operable member connected to said bail for actuating the same to release the brake arms.

2. In a typewriting machine, in combination, a tally-strip roll having disks at the ends thereof, a carbon-strip roll, a platen around which the tally-strip and carbon-strip are fed with the carbon-strip outside, a single receiving roll for both strips, 80 spring-pressed brake members normally engaging said disks, a manually-operable member, and means whereby actuation of said member will withdraw both of said brake members to permit the tally-strip to 85 be drawn forward readily.

3. In a typewriting machine, in combination, a tally-strip roll having disks at the ends thereof, a carbon-strip roll, a platen around which the tally-strip and carbon-strip are fed with the carbon-strip outside, 100 a single receiving roll for both strips, spring-pressed brake members normally engaging said disks, a pivoted releasing device having arms extending beneath the brake 105 members, a bar connecting the arms, and a manually-operable member whereby the releasing device may be actuated.

4. In a typewriting machine, in combination, a tally-strip roll having disks at the 110 ends thereof, a carbon-strip roll, a platen around which the tally-strip and carbon-strip are fed with the carbon-strip outside, a single receiving roll for both strips, spring-pressed brake members normally 115 engaging said disks, a releasing device pivotally mounted on a rod and comprising arms extending from said rod and engaging under said brake members, a member extending along said rod and connected to said arms, and a manually-operable member 120 whereby the releasing device is actuated.

5. In combination, a platen and a tally-strip device comprising a frame having ends, a roll to receive both the tally-strip 125 and the carbon-strip when carried past the printing point, a tally-strip delivery roll, a carbon-strip delivery roll, split expanding tubes to engage the inner surface of said carbon-strip delivery roll, said tubes having 130

hubs lying in slots in the frame ends, one of said tubes being connected with the adjacent end of the tally-strip device so as to resist the movement of the carbon-strip roll, and 5 a handle on the other tube to enable rewinding of the carbon-strip.

6. In combination, a hollow web-supporting roll and supporting means therefor including a split expanding head adapted to 10 be forced into one end of the hollow roll, a pin projecting from said head, a support having a notch through which said pin extends, and a spring device on the pin outside of the support whereby pressure will be 15 exerted on the opposite sides of said support and rotation of said roll resisted.
7. In combination, a hollow web-supporting roll and supporting means therefor including a split expanding head adapted to be 20 forced into one end of the hollow roll, a pin projecting from said head, a support having a notch through which said pin extends, a member threaded on said pin outside of the support, a second member mounted on said 25 pin between the first member and the support, and a spring between said members whereby pressure will be exerted on the opposite sides of the support and rotation of the roll will be resisted.
- 30 8. In combination, a hollow web-supporting roll and supporting means therefor including a split expanding head adapted to be forced into one end of the hollow roll, a pin projecting from said head, a support having a notch through which said pin extends, a hollow cylindrical member having a reduced inner end fitting loosely on the pin, a nut fitting in the end of said cylindrical member and threaded on said pin, and a 35 spring interposed between said nut and a shoulder in said cylindrical member formed by the reduced portion.

9. In combination, a hollow web-supporting roll and supporting means therefor including a split expanding head adapted to 40

be forced into one end of the hollow roll, a pin projecting from said head, a support having an open slot through which said pin extends, a collar on said pin outside the support, and a latch member pivoted at a point 50 substantially on the prolongation of the center line of said slot and having a concave portion to fit over the collar to hold the pin in position.

10. In combination, a hollow web-supporting roll and supporting means therefor including a split expanding head adapted to be forced into one end of the hollow roll, a pin projecting from said head, a support having an open slot through which said pin 60 extends, a collar on said pin outside the support, a latch member pivoted at a point substantially on the prolongation of the center line of said slot and having a concave portion to fit over the collar to hold the pin in 65 position, and detent means to hold the latch in either effective or ineffective position.

11. In a typewriting machine, in combination, a platen, a tally-strip roll, a carbon-strip roll, a roll for receiving said strips 70 while passing around the platen, braking means normally effective on the tally-strip roll, braking means for said carbon-strip roll, means to turn the receiving roll to unroll a tally-strip and carbon-strip when 75 the work is completed, a knife adjacent the receiving roll, means for turning the carbon-strip roll to rewind thereon the carbon-strip and draw the leading edge thereof back of the knife, and means to release the 80 braking means for the tally-strip roll to permit the latter to be drawn toward the receiving roll until the last line of writing thereon is above the knife, whereupon the used portion may be severed.
